DESIGN FOR A TOY FIGURE

Henry A. Nozewski, Detroit, Mich.

Application March 28, 1947, Serial No. 137,995

Term of patent 7 years

(Cl. D34—2)

To all whom it may concern:

Be it known that I, Henry A. Nozewski, a citizen of the United States of America, residing in Detroit, the county of Wayne and State of Michigan, have invented a certain new, original, and ornamental Design for Toy Figure, of which the following is a specification, reference being had therein to the accompanying drawing, forming a part thereof, wherein

Fig. 1 is a side elevation of the toy figure showing my new design; and

Fig. 2 is a front elevation of the toy figure shown in Fig. 1.

I claim:

The ornamental design for a toy figure, substantially as shown.

HENRY A. NOZEWSKI.
